UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

FILING AND INDEXING EQUIPMENT.

Application filed May 31, 1918. Serial No. 237,392.

To all whom it may concern:

Be it known that I, JOHN T. QUIGLEY, a citizen of the United States, and a resident of Boston, in the county of Suffolk and 5 State of Massachusetts, have invented an Improvement in Filing and Indexing Equipments, of which the following description, in connection with the accompanying drawings, is a specification, like characters 10 on the drawings representing like parts.

This invention relates to indexes and files, and is more especially concerned with an equipment of the so-called loose-leaf, visible index type in which the successive leaves or 15 sheets overlie one another in such manner that their margins present their index-bearing edges substantially in one plane, so that the number, name or subject-matter index may be scanned quickly without handling 20 each leaf.

My invention will be best understood by reference to the following description when taken in connection with the accompanying drawings of one specific embodiment thereof, while the scope will be more particularly 25 pointed out in the appended claims.

In the drawings,—

Fig. 1 is a front elevation of an indexing and filing equipment embodying my invention; 30

Fig. 2 is a side elevation of the same;

Fig. 3 is a sectional view on a much enlarged scale on line 3—3 of Fig. 1 illustrating a sheet-holder and the sheet-holder locking means in their normal positions; 35

Fig. 4 is a sectional view similar to Fig. 3, but showing the sheet-holder locking means unlocked and one end of the sheet-holder brought forward preparatory to withdrawing same from its place;

Fig. 5 is a sectional view on a much enlarged scale on line 5—5 of Fig. 1;

Fig. 6 is a sectional view on line 6—6 of Fig. 1, showing some of the leaves in an up-standing position and others in a depending position, and illustrating the rocking action of the sheet-holders;

Fig. 7 is a cross-sectional view of one of the sheet-holders equipped with a two-leaf sheet having a folded margin to lock the same in place in the sheet-holder;

Fig. 8 is a similar sectional view, showing a single-leaf sheet whose margin is folded several times upon itself to form a plurality of thicknesses within the sheet-holder;

Fig. 9 is a sectional view similar to Figs. 7 and 8, but showing a single-leaf sheet locked in the sheet-holder by having its margin folded once upon itself; and

Fig. 10 is a sectional view on line 10—10 of Fig. 1.

Referring to the drawings and to the embodiment of my invention which I have selected for illustration, I have there shown an indexing and filing equipment comprising a pair of guides 11 and 12 forming a track for a plurality of suitable sheet-carriers or holders 13, the latter, in the present example, being in the form of cylindrical tubes whose opposite ends are suitably guided by the guides 11 and 12. In the present instance, these guides are provided with channels 14 and 15 respectively, and they may be formed by inwardly turned flanges 16 and 17 on a plate 18 which constitutes a 75 mounting for the equipment.

As best shown in Fig. 3, the flanges 16 and 17 normally overlie the ends of the sheet-carriers or holders 13. As a means for normally locking the latter against end-wise movement, I have herein provided a locking bar 19 which may consist of a flat metallic strip, shown in cross-section in Fig. 3 and having its terminal portions reduced as best shown in Fig. 1 to form shafts 20 80 mounted in suitable bearings 21, the latter, in the present example, being in the form of blocks inserted in the upper and lower ends of the channel 15 and secured in place by rivets 22, best shown in Fig. 1, extending 85 through the flange 17 and plate 18.

When the locking bar 19 is in its normal position illustrated in Fig. 3, the sheet-carriers and holders 13 are permitted to move endwise to a slight extent necessary to give 95 them proper clearance, but are locked against removal from the guides 16 and 17, since the amount of normal end play is insufficient to permit the escape of the sheet-carriers or holders. When, however, the 100 pivoted locking bar 19 is swung from its locking position, shown in Fig. 3, to the unlocked position, shown in Fig. 4, (in the present example through an arc of approximately ninety degrees) the bar is presented 105 flatwise instead of edgewise to the ends of the sheet-carriers or holders, and hence any one or more of the latter may be moved lengthwise to a greater extent into the channel 15, thus freeing them from the channel 110

14, whereupon their ends may be swung in an outward direction as illustrated in Fig. 4. Thus, it is evident that the sheet-carriers or holders are normally positively locked in place with relation to the guides, and are thus prevented from being accidentally removed while still permitting them to be unlocked and withdrawn instantly when desired.

10 Preferably suitable means are provided normally to retain the locking bar 19 in its carrier-locking position and to restore said bar to such position after having been displaced therefrom. Such means may take 15 various forms, but I prefer to provide one or more suitable springs 23 appropriately connected to the locking bar 19 as by providing the latter with arms 24, one of which is clearly shown in Fig. 5, to which one end 20 of the spring is attached, the other end being secured to a suitable fixed point which in the present example is in the form of a rivet 25. Herein the upper and lower margins of the plate 18 are bent to form inwardly turned flanges 26, best shown in 25 Fig. 1, which form upper and lower stops limiting the upward and downward movement of the sheet-carriers or holders 13 with their attached sheets. If desired, these 30 flanges may form convenient chambers 27, into which the springs 23 may extend, and the rivets 25 to which the springs are attached may extend through the flanges 26 and the back plate 18.

35 From an inspection of Fig. 5 compared with Fig. 3, it will be evident that each of the springs 23 exerts a pull on its arm 24 in the proper direction normally to maintain the locking bar 19 in the position shown in 40 Fig. 3, thereby to prevent undue lengthwise displacement of the sheet-carriers or holders 13. When, however, the locking bar is turned from the position shown in Fig. 3 to that shown in Fig. 4 in opposition 45 to the tension of the spring, the sheet carrier or holder is unlocked and can be removed as already described. As a convenient means for operating the locking bar to unlock the sheet carriers or holders, I 50 have herein provided said bar with a thumb or finger piece 28, which in the present example is suitably secured to the bar, as by rivets 29, and projects therefrom through a suitable opening 30 in the guide 12, as best shown in Figs. 1 and 2. This opening is, of 55 course, made great enough in extent, as shown in Figs. 3 and 4, to permit the thumb or finger piece 28 to be swung through an angular distance sufficient to carry the locking bar 19 from its locking to its locked position.

60 The sheet-carriers or holders 13, as already stated, are preferably in the form of cylindrical tubes. Since they are cylindrical, their ends constitute trunnions about

whose axes they may be turned, thus carrying their attached leaves. Their cylindrical form, moreover, maintains them and their leaves uniformly spaced and held in proper position lengthwise of their guides 11 and 12. Since this is so, the sheets and their carriers or holders may be turned freely about the axes of the latter, thus rendering both faces of the sheets readily accessible for the purpose of inspection and making of 75 records, as will be evident from an inspection of Fig. 6, wherein some of the sheets are shown in upstanding position and others depending.

80 The sheets may take various forms and may be otherwise appropriately secured to their respective carriers or holders. In the present example, the latter are provided with narrow, longitudinal, sheet-receiving slots 31 leading into longitudinal sheet-receiving chambers 32. In the form illustrated in Fig. 6, I have provided sheets 33, each of which is folded upon itself to form a double-leaf sheet, whose fold extends through the slot 31 into the chamber 32, and in the fold is a locking rod 34, preferably somewhat larger in cross-section than the width of the slot 31. By first introducing the locking rod into the fold of the sheet, and then sliding the latter lengthwise into the slot, even the thinnest sheet can be locked into its carrier or holder in a positive and perfectly secure manner, so that it cannot be removed therefrom except by first 90 removing the carrier or holder from its place in the guides. When, however, the sheet-carrier or holder is removed from its guides, the sheet may be separated therefrom by relatively moving the sheet and sheet-carrier or holder in opposite directions lengthwise of the latter, with a sliding motion. The rod 34 may then be removed from the fold, if desired. It is also evident that the sheet might be removed from the sheet-carriers or holders by first withdrawing the rod 34 lengthwise from the fold and then pulling the latter in an outward direction 95 from the slot.

100 In Fig. 7, I have shown a sheet 35 similar to the sheet 33, and having a folded marginal portion 36 interlocked with the sheet carrier or holder 13, but in this case, the rod is omitted and the locking of the sheet is accomplished by making a second fold so disposed that the width of the folded marginal portion is at least as great as the internal diameter of the chamber 32. Preferably the width of the slot 31 is only slightly greater than the combined thickness of both leaves of the sheet 33, so that the latter is effectually locked in place in the carrier or holder. In Fig. 8, I have shown a single sheet 37, having a marginal portion 38 which is folded upon itself several times to give the same increased stability and durability in the case 110 115 120 125 130

- of thin paper. In Fig. 9, I have shown a single sheet 39 of considerable thickness having a folded margin 40 similar to the margin 36 in Fig. 7, and acting in like manner to retain the sheet in its carrier or holder. Any or all of these forms of leaves with their locking devices may be employed in a single equipment, thus adapting the latter to light or heavy weight cards or sheets, both kinds being used with equal facility and being susceptible of arrangement and re-arrangement from time to time, and detachment and re-attachment to any of the sheet-carriers or holders.
- 15 Preferably the length of the plate 18 is such as to receive and hold a definite number of sheet carriers or holders with their attached sheets, the latter overlying one another, and the lower edge of the lowermost leaf preferably terminating adjacent the lower edge of the holder. To this end, the carrier or holder of the lowermost sheet may be spaced from the lower edge of the plate in any suitable manner, as, for example, by the use of a sufficient number of empty sheet-carriers and holders filling the space, or by the use of a single spacing element 41, the latter being supported by the lower flange 26 of the plate 18. This spacing element, like the sheet carriers or holders, may be removed and replaced at will by, and is normally locked in place by the locking bar 19.
- 35 While I have herein shown and described one form or embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made without departing from the principles thereof.
- Having thus described one embodiment of my invention, what I claim and desire by Letters Patent to secure is:
- 50 1. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and means to lock said sheets against detachment from said sheet-holders.
- 55 2. A filing or indexing equipment comprising, in combination, a pair of sheet-holder supports, a plurality of sheet-holders terminating at opposite ends in said supports but detachable therefrom upon endwise movement, locking and unlocking means normally to lock said sheet-holders in said sheet-holder supports against movement transversely of said supports, sheets held by said sheet-holders respectively, and means to lock said sheets against detachment from said sheet-holders.
- 60 3. A filing or indexing equipment comprising, in combination, a pair of sheet-holder supports, a plurality of sheet-holders terminating at opposite ends in said supports but detachable therefrom upon endwise movement, locking and unlocking means normally to lock said sheet-holders in said sheet-holder supports against movement transversely of said supports, sheets held by said sheet-holders respectively, and means to lock said sheets against detachment from said sheet-holders.
- 65 4. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 70 5. A filing or indexing equipment comprising, in combination, a pair of sheet-holder supports, a plurality of sheet-holders terminating at opposite ends in said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 75 6. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 80 7. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 85 8. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 90 9. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 95 10. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 100 11. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 105 12. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 110 13. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 115 14. A filing or indexing equipment comprising, in combination, a pair of sheet-holder supports, a plurality of sheet-holders supported at opposite ends by said supports but detachable therefrom upon endwise movement, locking and unlocking means normally to lock said sheet-holders in said sheet-holder supports against movement transversely of said supports, sheets held by said sheet-holders respectively, and having opposite edges interposed between said supports, and means to lock said sheets in said sheet-holders.
- 120 15. A filing or indexing equipment comprising, in combination, a pair of parallel guideways, a plurality of sheet-holders extending transversely and mounted to slide longitudinally of said guideways but detachable therefrom upon endwise movement, locking and unlocking means normally to lock said sheet-holders against removal from said guideways, by movement transversely of said guideways, sheets held by said sheet-holders respectively, and means to lock said sheets against detachment from said sheet-holders.
- 125 16. A filing or indexing equipment comprising, in combination, a pair of parallel guideways, a plurality of sheet-holders extending transversely and mounted to slide longitudinally of said guideways but detachable therefrom upon endwise movement, locking and unlocking means normally to lock said sheet-holders against removal from said guideways, by movement transversely of said guideways, sheets held by said sheet-holders respectively, and means to lock said sheets against detachment from said sheet-holders.
- 130 17. A filing or indexing equipment comprising, in combination, a pair of parallel

guideways, a plurality of sheet-holders extending transversely and mounted to slide longitudinally of said guideways but detachable therefrom upon endwise movement, 5 sheet-holder locking and unlocking means normally retaining said sheet-holders positively locked in place with relation to said guideways to prevent removal therefrom by movement transversely of said guideways, 10 and sheets normally interlocked with said sheet-holders and prevented from being detached therefrom while said sheet-holders are locked in place in said guideways.

8. A filing or indexing equipment comprising, in combination, a track, a plurality of sheet-carriers mounted to move longitudinally of said track but detachable therefrom by endwise movement transversely of the track, locking and unlocking means normally to lock said sheet-carriers against detachment from said track by movement transversely of said track, a plurality of sheets carried by said sheet-carriers, and means to lock said sheets against detachment 25 from said sheet-carriers.

9. A filing or indexing equipment comprising, in combination, a track, a plurality of sheet-carriers mounted to move longitudinally of said track but detachable therefrom by endwise movement transversely of the track, locking and unlocking means normally to lock said sheet-carriers against detachment from said track by movement transversely of said track, a plurality of 35 sheets carried by said sheet-carriers, means to lock said sheets against detachment from said sheet-carriers by movement of said sheets longitudinally of said track, said means and said carriers being adapted to 40 allow the sheets to be detached from the carriers by transverse movement, but only when the carriers are detached from the track.

10. A filing equipment comprising, in combination, a series of sheet-carriers and a support therefor presenting means overlying the ends of said sheet-carriers, two abutments for the ends of said sheet-carriers normally to prevent their removal by endwise movement and having provision for movement of one abutment relatively to the other to permit detachment of said sheet-carriers by endwise movement, and means for causing said movable abutment normally to lock said 55 sheet-carriers positively against removal by endwise movement.

11. A filing or indexing equipment comprising, in combination, a pair of channeled guides, a plurality of sheet-carriers having their opposite ends terminating in the channels of said guides, respectively, and sheet-carrier locking and unlocking means normally locking said sheet-carriers against substantial movement transversely of said guides and adapted to be unlocked to per-

mit said sheet-carriers to be moved endwise and detached from said guides.

12. In a filing or indexing equipment, the combination of a support provided with a pair of flanges extending towards each other and forming opposed sheet-holder receiving channels, a plurality of sheet-holders greater in length than the space between said flanges and having their opposite ends normally covered by said flanges, and sheet-holder locking and unlocking means normally locking said sheet-holders against endwise movement and adapted to unlock said sheet-holders to permit the latter to be moved endwise, thereby to withdraw their ends from beneath one of said flanges. 75

13. A filing or indexing equipment comprising, in combination, sheet-holder supporting means, sheet-holders supported thereby, sheets held by said sheet-holders, and sheet-holder positive locking means adapted to engage said sheet-holders endwise. 85

14. A filing equipment comprising, in combination, sheet-holder supporting means, sheet-holders supported thereby, sheets held by said sheet-holders, and sheet-holder positive locking means including a single locking element adapted to present an obstruction to removal of said sheet-holders by endwise movement and mounted to move laterally to remove such obstruction to permit removal of said sheet-holders by lengthwise movement, and means normally to retain said element in a position in which it is immovable by endwise thrust of said sheet-holders thereagainst and thereby positively locks said sheet-holders against removal by endwise movement. 95

15. A filing or indexing equipment comprising, in combination, sheet-holder supporting means, sheet-holders supported thereby, sheets held by said sheet-holders, and sheet-holder locking means including a pivoted locking-bar. 100

16. A filing or indexing equipment comprising, in combination, sheet-holder supporting means, sheet-holders supported thereby, sheets held by said sheet-holders, and sheet-holder locking means including a pivoted locking-bar extending along said sheet-holders. 115

17. A filing or indexing equipment comprising, in combination, sheet-holder supporting means, sheet-holders supported thereby, sheets held by said sheet-holders, and sheet-holder positive locking means including a locking element limiting movement of said sheet-holders longitudinally of the latter, and yielding means normally retaining said element in its sheet-holder locking position. 120

18. A filing or indexing equipment comprising, in combination, sheet-holder supporting means, sheet-holders supported

- thereby, sheets held by said sheet-holders, and sheet-holder positive locking means normally presenting a limiting stop to limit movement of said sheet-holders longitudinally of the latter and mounted for movement to another position to permit removal of said sheet-holders from said supporting means.
19. In a filing or indexing equipment, the combination of a support provided with a pair of flanges extending towards each other and forming opposed sheet-holder receiving channels, a plurality of sheet-holders greater in length than the space between said flanges and having their opposite ends normally covered by said flanges, and sheet-holder positive locking and unlocking means normally positively locking said sheet-holders against endwise movement and adapted to unlock said sheet-holders to permit the latter to be moved endwise, thereby to withdraw their ends from beneath one of said flanges, said locking and unlocking means including a locking-bar extending lengthwise of and adjacent the other flange.
20. In a filing or indexing equipment, the combination of a support provided with a pair of flanges extending towards each other and forming opposed sheet-holder receiving channels, a plurality of sheet-holders greater in length than the space between said flanges and having their opposite ends normally covered by said flanges, and sheet-holder locking and unlocking means normally locking said sheet-holders against endwise movement and adapted to unlock said sheet-holders to permit the latter to be moved endwise, thereby to withdraw their ends from beneath one of said flanges, said locking and unlocking means including a locking-bar extending lengthwise of and adjacent the other flange and pivoted to swing toward and from said sheet-holders.
21. In a filing or indexing equipment, the combination of a support provided with a pair of flanges extending towards each other and forming opposed sheet-holder receiving channels, a plurality of sheet-holders greater in length than the space between said flanges and having their opposite ends normally covered by said flanges, and sheet-holder locking and unlocking means normally locking said sheet-holders against endwise movement and adapted to unlock said sheet-holders to permit the latter to be moved endwise, thereby to withdraw their ends from beneath one of said flanges, said locking and unlocking means including a locking-bar extending lengthwise of and adjacent the other flange and pivoted to swing toward and from said sheet-holders, and yielding means urging said bar toward said sheet-holders.
22. A filing device comprising, in combination, a hollow sheet-holder, a sheet held thereby, and means positively locking said sheet to said sheet-holder, said means comprising a locking element within said sheet-holder and mounted to move relatively to said sheet and sheet-holder, and a mounting having provision normally to prevent unlocking of said sheet from said sheet-holder.
23. A filing device comprising, in combination, a hollow sheet-holder, a sheet held thereby, and means positively locking said sheet to said sheet-holder, said means comprising a locking element within said sheet-holder and mounted to move longitudinally of the adjacent edge of said sheet and sheet holder, and a mounting having provision normally to limit such longitudinal movement.
24. A filing device comprising, in combination, a sheet, and sheet-holding means comprising two parts relatively movable longitudinally of the adjacent margin of said sheet, and a mounting having provision normally to limit such longitudinal movement.
25. A filing device comprising, in combination, a sheet, and sheet-holding means comprising two parts movable relatively to each other and to said sheet longitudinally of the adjacent margin of the latter, and a mounting having provision normally to limit such longitudinal movement.
26. A filing device comprising, in combination, a sheet and sheet-holding means comprising two parts relatively movable longitudinally of the adjacent margin of said sheet, one of said parts extending through said sheet, and a mounting having provision normally to limit such longitudinal movement.
27. A filing device comprising, in combination, a sheet and sheet-holding means comprising two parts relatively movable longitudinally of the adjacent margin of said sheet, one of said parts extending through a fold of said sheet, and a mounting having provision normally to limit such longitudinal movement.
28. A filing device comprising, in combination, a hollow sheet-holder, a sheet having a fold extending into said sheet-holder, and sheet-locking means in the fold of said sheet, and a mounting having provision normally to limit such longitudinal movement.
29. A filing device comprising, in combination, a tubular sheet-holder provided with a longitudinal slot, a sheet having a fold extending through said slot into the interior of said sheet-holder, and sheet-locking means in the fold of said sheet, and a mounting having provision normally to limit such longitudinal movement.
30. A filing device comprising, in combination, a tubular sheet-holder provided with a longitudinal slot, a sheet having a fold extending through said slot into the in-

terior of said sheet-holder, and a sheet-locking rod in the fold of said sheet, and a mounting having provision normally to limit such longitudinal movement.

5 31. A filing equipment comprising, in combination, a track, a series of sheet-carriers received by said track, means preventing movement of said sheet-carriers longitudinally of said track, positive locking means

normally positively locking said sheet-carriers against removal transversely of said track and having provision to unlock said sheet-carriers to permit their removal from said track by movement transversely of the latter.

In testimony whereof, I have signed my name to this specification.

JOHN T. QUIGLEY.
